(57) **CLAIM**

The ornamental design for a handle for chest expander, as shown and described.

DESCRIPTION

FIG. 1 is a perspective view of a handle for chest expander showing my new design;

FIG. 2 is a top plan view thereof;

FIG. 3 is a rear view thereof;

FIG. 4 is a left side view thereof;

FIG. 5 is a right side view thereof;

FIG. 6 is a front view thereof;

FIG. 7 is a rear view thereof; and,

FIG. 8 is a top plan view thereof, wherein the broken line showing of the chest expander is for illustrative purposes only and forms no part of the claimed design.
